(57) **CLAIM**

We claim the ornamental design for a lighting device, as shown and described.

DESCRIPTION

FIG. 1 is a front, top and side environmental perspective view of a lighting device, showing our new design;

FIG. 2 is a rear, second side and bottom environmental perspective view thereof;

FIG. 3 is a front, top and side perspective view thereof;

FIG. 4 is a rear view thereof;

FIG. 5 is a front view thereof;

FIG. 6 is a top plan view thereof;

FIG. 7 is a bottom plan view thereof;

FIG. 8 is a side view thereof;

FIG. 9 is a second side view thereof; and,

FIG. 10 is a rear view thereof.

The broken line showing is superimposed on the continuous surface of the claimed design, is for illustrative purposes only, and forms no part of the claimed design.
